UNITED STATES PATENT OFFICE.

ELLIS C. COHEN, OF WILLIMANTIC, CONNECTICUT.

GAME.

1,341,360.

Specification of Letters Patent.

Patented May 25, 1920.

Application filed April 24, 1918. Serial No. 230,475.

To all whom it may concern:

Be it known that I, ELLIS C. COHEN, a citizen of the United States, residing at Willimantic, in the county of Windham, State of Connecticut, have invented certain new and useful Improvements in Games; and I do hereby declare the following to be a full, clear, and exact description of the invention, such as will enable others skilled in the art to which it appertains to make and use the same.

The invention relates to a game device, and has for its primary object to provide a device of this character, wherein the players will be required to exercise their thinking faculties to master the game and at the same time afford attraction and amusement for the players.

Another object of the invention is the provision of a game device of this character wherein a series of movable subordinate objects and a master object are employed, the game being designated "The Wolf and the Sheep" or "Bagging the Kaiser," and the series of subordinate objects are distinguished and entitled "sheep" while the master object is entitled "wolf" and these objects are movable in prescribed courses upon a playing board having demarcations representative of a central and corner fields or goals, the fields or goals being checkered or subdivided, simulating a checker or chess board, and the object is to trap the "wolf" object or capture the "sheep" objects, thus the winner of the game being determined resultant therefrom.

The invention is hereinafter more fully described and pointed out in the claim hereunto appended.

40 In the accompanying drawing:—

Figure 1 is a plan view of the game board constructed in accordance with the invention;

Fig. 2 is a sectional view thereof;

45 Fig. 3 is a plan view of one of the subordinate objects;

Fig. 4 is a plan view of the master object.

Similar reference characters indicate corresponding parts throughout the several 50 views in the drawing.

In carrying the invention into practice a game board A is provided having printed or otherwise indicated or marked on its upper face an intermediate or center square 5 and corner squares 6 each of equilateral rectangular shape. The center and corner

squares each is subdivided by cross lines into grouped smaller squares 7 while these squares are further subdivided by the crossed diagonal long and short lines 8 and 9 respectively. The center square 5 forms a field or goal common to all the players, while the squares 6 at the corners are for the opponent players and constitute fields or goals.

65

Adapted to be placed and moved upon the board A over the playing surface thereof are series of subordinate objects each in the form of a small disk 10 and a master object 11 in the form of a large disk, the board A 70 being preferably made from pasteboard, although it may be made from any other material, while the disks 10 and 11 are made from wood, yet the same may be made from other material. The smaller disks 10 are 75 indicated or designated "sheep," while the larger disk 11 is indicated or designated "wolf." There are twelve disks 10 and a single disk 11 employed in playing the game, and but two players can be opponents in 80 the playing of the game, that is to say, the game can be played by only two persons.

In the playing of the game, to start the object 11 designated "wolf" can be placed anywhere on the playing face of the board 85 A. The disks 10 designated "sheep" are placed one by one on the playing face of the board until the number has been exhausted. The players alternately move their objects such as the disks 10 and 11. The "wolf" 90 and "sheep" can be moved anywhere on the fields of the playing surface of the board A, the movements of the "wolf" being controlled by one player and the movements of the "sheep" controlled by the other player, 95 but after the start the sheep subsequent to being placed cannot be moved until all of the other "sheep" have been positioned upon the board. The "wolf" is allowed to capture any "sheep," but the sheep are not 100 allowed to do this, the object being to force the "wolf" into such a position that it cannot be moved. The "wolf" can capture a "sheep" by jumping him as in a game of ordinary checkers. Should the "wolf" capture all of the sheep the game is given to the opponent controlling the movements of the same, but should the "wolf" be forced by the other player into a position that it cannot be moved, said other player wins the 105 game. It is of course understood that the disks in their movements are required to be

moved into and from squares in the fields or goals in the progress of the game.

In playing the game "Bagging the Kaiser" the "wolf" can be designated the kaiser and the "sheep" designated as soldiers.

From the foregoing it is thought that the mode of playing the game and the manner of use of the device therefor will be clearly

10 understood, and therefore a more extended explanation has been omitted. Rules may be mutually agreed upon for playing the game, and to vary and make the same attractive and interesting.

15 What is claimed is:

A game apparatus comprising a board

having central and corner squares thereon with their sides parallel with corresponding sides of the board and with the inner corners of the corner squares touching the corresponding corners of the inner square, each square having marked thereon its diagonal and its diameters intersecting at their centers and objects of different appearance movable over the board.

20 In testimony whereof, I affix my signature, in the presence of two witnesses.
